UNITED STATES PATENT OFFICE.

FRANK WILLIS MAYES, OF HOPKINSVILLE, KENTUCKY.

LINEMAN'S CHAIR.

1,117,211.

Specification of Letters Patent.

Patented Nov. 17, 1914.

Application filed May 5, 1913. Serial No. 765,500.

To all whom it may concern:

Be it known that I, FRANK W. MAYES, a citizen of the United States, residing at Hopkinsville, county of Christian, and State of Kentucky, have invented certain new and useful Improvements in Linemen's Chairs, of which the following is a specification.

My invention relates to linemen's chairs, that is, to a traveling seat adapted to be supported upon the messenger wire to accommodate the lineman when attaching a cable to said wire.

The object of my invention is to provide a device of the class mentioned which may be readily placed upon the messenger wire and which cannot accidentally be displaced therefrom while in use through the neglect of the lineman to take the proper precautions.

20 A further object of my invention is to provide a device as mentioned which may be easily propelled along the messenger wire by the lineman and equipped with means for locking the same at any desired position.

25 A further object of my invention is to provide a device with an improved cable raising and supporting device and which shall not interfere with placing the device on the wire.

30 Other objects will appear hereinafter.

With these objects in view my invention consists generally in a pair of hangers provided at their upper ends with grooved wheels adapted to travel upon the messenger 35 wire and a pair of horizontally disposed longitudinal members forming the seat and spaced apart to permit the device to be placed astride the wire.

My invention further consists in a device 40 as stated further characterized by means for locking one of the wheels against rotation to secure the chair in any desired position upon the wire.

My invention further consists in a chair 45 as stated further characterized by being equipped with a cable wheel or pulley rotatably mounted upon a shaft arranged upon one of said hangers and of such construction that the same may be swung out of position 50 when placing the chair upon the wire.

My invention further consists in various 55 details of construction and arrangements of parts all as will be fully described herein- after and particularly pointed out in the claims.

My invention will be more readily understood by reference to the accompanying drawings forming a part of this specification and in which—

Figure 1 is a perspective view of a lineman's chair embodying my invention in its preferred form, Fig. 2 is an end elevation of the same, and Fig. 3 is a detail sectional view through the upper portion of one of the hangers and illustrating the means for locking one of the wheels against rotation.

The chair comprises a pair of similar hangers 1 and 2 respectively and a seat 3. The hangers are each formed of a single metal strap bent upon itself to form a pair 70 of diverging depending arms 4—4 having their lower ends turned horizontally inwardly as at 5 to support the seat 3. The seat 3 is formed of two longitudinally disposed members 6 preferably of wood, and connecting the ends 5 of the respective hangers 1. A brace bar 7 connects the upper ends of the hangers. The upper portion of the arms 4 lie parallel to each other for a short distance as at 8 and are perforated 75 to form bearings for the axle of the wheels 9 which rest upon the messenger wire A. The arms are then bowed outwardly as at 10 to form an enlarged space for the cable B to pass through without touching the arms 80 and then diverging through the remainder of their lengths. The longitudinal members 6 of the seat 3 are spaced apart as illustrated in order that the device may be readily placed astride the wire A and to 85 facilitate initially raising the cable into position.

One of the wheels 9 is provided with a transverse aperture or perforation 11 which is adapted to register with perforations 12 95 in the portions 8 of the respective hanger to receive a pin 13 for locking the wheel against rotation. The pin is provided with a chain or flexible member 14 securing the same to the hanger so that the same cannot 100 be accidentally dropped.

15 indicates a shaft provided with an eye 16 pivotally connected to one arm 4 of the hanger 1. The other end of the shaft is adapted to rest in a hook 17 formed upon the other arm of the hanger and rotatably mounted upon said shaft is a cable wheel 18, 105 contains 19 on the shaft 15 holding the wheel in position thereon when it is desired to place the device on the messenger wire and 110

- to initially place the cable on the wheel 18, the free end of the shaft 15 is lifted out of the hook 17 and the shaft swung to one side. After the device is in position on the 5 wire and cable lifted between the seat members 6 the shaft 15 and wheel 18 are swung into position beneath the cable and the end of the shaft dropped into the hook 17 after which the device is ready for use.
- 10 By having the hangers formed with two continuous arms extending from the wheels 9 to the seat 3 it is obvious that it is impossible to accidentally displace the device from the wire after being placed thereon 15 and that it is not necessary to provide auxiliary locking devices for this purpose. If preferred the wheels 9 may be provided with ball bearings 20 to facilitate moving the device along the messenger wire.
- 19 Having described my invention, I claim:
1. A lineman's chair comprising a pair of substantially inverted U-shaped hangers, wire engaging wheels mounted in the upper ends of said hangers and a pair of spaced longitudinal seat members connecting the lower ends of said hangers, said hangers terminating at the inner edges of said seat members, substantially as described.
  2. A lineman's chair comprising a pair of substantially inverted U-shaped hangers, wheels mounted in the upper end of said hangers, a seat connecting the lower ends of said hangers, said wheels and the adjacent portions of said arms being provided with apertures adapted to register and a pin adapted to be inserted in said apertures for locking one of said wheels against rotation, substantially as described.
3. A lineman's chair comprising a pair of hangers, each hanger formed of a single strip of material bent upon itself forming a pair of similar depending arms, said arms being substantially parallel for a short distance at their upper portions and then diverging downwardly, a pair of spaced seat members secured to the lower ends of said arms, wheels mounted between the parallel portions of said arms, said wheels and the adjacent portions of said arms being provided with apertures adapted to register and a pin adapted to be inserted in said apertures, substantially as described.
4. A lineman's chair comprising a pair of substantially inverted U-shaped hangers, each formed of a single strip of material, wheels mounted in the upper portions of said hangers, a pair of spaced longitudinal seat members connecting the lower ends of said hangers, said hangers terminating at the inner edges of said seat members, a shaft pivotally connected at one end to one arm of one of said hangers, a hook adapted to receive the other end of said shaft and a cable wheel mounted on said shaft, substantially as described.

In testimony whereof I have signed my name to this specification in the presence of two subscribing witnesses.

FRANK WILLIS MAYES.
